UNITED STATES PATENT OFFICE.

CARL G. KOPPITZ, OF GREENSBURG, PENNSYLVANIA, ASSIGNOR TO RAILWAY AND INDUSTRIAL ENGINEERING COMPANY, OF GREENSBURG, PENNSYLVANIA, A CORPORATION OF PENNSYLVANIA.

HIGH-TENSION SWITCH MECHANISM.

Application filed October 18, 1920. Serial No. 417,540.

The tendencies in the art of the electrical transmission of power over considerable distances has taken a very decided turn towards the use of extremely high voltages. Heretofore the systems of electric power transmission have been limited to rather restricted areas seldom covering any one State but usually only a comparatively small part of any one State. The transmission of power over these areas has been accomplished by the use of voltages never in excess of one hundred and fifty or one hundred and sixty thousand volts but usually ranging between sixty-six and one hundred and thirty thousand volts. The present tendency is towards the installation of what is called a super-power line having as its objective the tying together electrically of a large number of the present transmission systems into one network covering possibly six or eight States. A primary idea is to equalize the demand from any one system and thereby reduce a large part of the usual standby-equipment, increase the reliability of service and to increase the load factors, thereby materially reducing the operating expenses.

It will be essential on a system such as outlined to do a considerable part of the switching on the high tension side but the industry finds itself in the position that no suitable switch for two hundred and twenty thousand volts has been developed. The oil switch is capable of development for such voltage but will necessarily be very expensive. If a suitable air break switch were available this switching could be done with very much more reasonable investment.

A study of the various forms of porcelains that are on the market leads readily to the conclusion that none are suitable as switch insulators for the voltages contemplated. Their first difficulty lies in their mechanical weakness when built up to a height suitable for these extreme voltages.

In analyzing the fundamentals of the present standards that are designed it will be noted that these insulators are so constructed as to subject the porcelain to its safeulti-

mate breakdown capacity thereby requiring the very highest grade of material likewise designed with such dimensions that therefore the strength can not be materially increased owing to the relative shrinkage of the porcelain and metal parts.

It is one object of the invention to provide an insulator construction which avoids the necessity of using the highest grade of materials and which at the same time secures a higher degree of mechanical strength at lower cost.

Another object is to secure a construction that would more readily permit such insulators being used in the construction of switching apparatus by providing a hollow interior protected from the weather through which the switch may be operated without possibility of interference from the weather, particularly sleet.

In general the insulators at present used are so designed as to put the porcelain under compression which accounts for the fact that the insulation is worked at such high unit stresses. In the present design it is proposed to work the insulation under tension and make the insulator of such form as to limit the tension to safe values. It is proposed to make this insulator in the customary well known form of stoneware pipe with bell and socket connections cemented together without the use of hardware thereby eliminating the weak features of the present customary designs of the relative expansions of a metal and porcelain. Further it will be seen that this material is electrically stressed in a longitudinal direction thereby imposing a minimum unit stress on the material, permitting a working stress of say seven hundred and fifty to one thousand volts per inch of insulating material whereas in the ordinary design of porcelain insulator this stress may run anywhere from twenty to forty thousand volts per inch. For this reason a much lower grade of ceramic material may be used than that heretofore demanded for insulator constructions.

For a full understanding of the inven-

tion reference is had to the accompanying drawings in which—

Fig. 1 is a vertical sectional view of a device constituting the invention:

5 Fig. 2 is an elevation of a switch construction embodying the invention; and

Fig. 3 is a plan view of the construction shown in Fig. 2.

The principal part of the invention is a 10 hollow column of ceramic material of the form commonly used for sewer pipes. The column is composed of a plurality of sections 1 provided with the bells 1^a as is customary in sewer pipe construction. The 15 sections, which have an inside diameter of approximately 24", are cemented together to make a solid structure about fifteen feet high.

Of the various materials I have tried, 20 such as common sewer pipe, firebrick in stoneware crocks and chemical stoneware, I find the latter as best suited for the purposes of the invention. There is, of course, considerable latitude in the selection of the 25 material for making the tiles. I contemplate the use of any material from which the tiles can be cheaply made and which affords a sufficient electrical resistance.

The column is in practice supported up- 30 on a concrete base 3 and anchored thereto by any suitable means as by means of rods 4 and a collar 5 bearing upon the bell flange of the lowermost of the tile sections. The joint between the collar 5 and the column 35 is preferably sealed by a layer of cement.

At its upper end the column carries 40 switch blades 6. In the particular instance shown the blades 6 constitute a so called vertical break switch. The blades 6 are pivotally supported upon a frame 7 by means of pins 8 journaled in bearings 9. Each of the pins 8 carries a pinion 10 which engages a beveled gear 11 keyed upon a shaft 12.

45 The shaft 12 in turn carries a beveled gear which is in mesh with a beveled gear 13 mounted upon the end of a stub shaft 14 disposed axially of the column. The stub shaft 14 is secured to the upper end of a 50 smaller column 15 which extends downwardly through the column and carries at its lower end another stub shaft 16.

The column 15 is also composed of a plurality of tile sections cemented together and 55 carries at its upper and lower ends metallic caps 17 and 18 respectively to which the stub shafts 14 and 16 are secured.

The concrete base 3 has a depression defining a chamber for receiving the lower end 60 of the column, a metallic frame 19 for supporting the column and centering the shaft 16, a gear 20 on the shaft 16 and an electric motor 21 for driving the gear 20.

For the sake of simplicity I have shown 65 and described only so much of the mecha-

nism as is necessary for operating the switch blades. In practice, however, I contemplate the use of auxiliary mechanism such as over-load relays and connecting elements for automatically operating the switch when an 70 overload or a short circuit occurs on the line. Such mechanism may be conveniently housed within the column and effectively protected together with the other mechanism enclosed therein. 75

As shown in Figs. 2 and 3, a switch for breaking a high tension line may include a central column 22 carrying the switch blades 25 and columns 23 and 24 carrying stationary contacts 26 and 27 respectively and 80 horns 28 and 29.

These insulators can be cheaply made of such a size as to permit the safe operation of very long switch blades thereby securing 85 a very large break or gap in the opening of the switch. In the design proposed the lengths of the blades are of the order of fourteen feet each, which upon opening simultaneously cause a break between the tips of the horns of approximately fifty-one 90 feet between the tips of the arcing horns.

The usual form of insulator is equipped 95 with petticoats 2 in order to insure that a portion of the surface between the metal parts is maintained in a dry condition but it is obvious that if the voltage stress per unit length is sufficiently low that it will not be necessary to have any portion of the surface of the insulating column kept dry. The total length of the column as proposed 100 for two hundred and twenty thousand volts is approximately fifteen feet which reduces the voltage stress per inch to about eight hundred volts which appear to be safe against surface over-flash. If, however, this 105 is found not to be safe it will be possible to equip the column with some form of shields or petticoats to insure a portion of its surface remaining dry.

A three-phase transmission line would 110 require three switch units such as shown in Figs. 2 and 3 and a separate motor would be used for operating each switch unit, the different motors to be electrically interconnected for operation in unison.

In the claims the term "column" is intended to define a structure of considerable height approaching fifteen feet in height and rising from the ground, in contradistinction to insulators of relatively small size 120 supported on walls, masts or poles.

I claim:

1. High tension switch mechanism including a hollow column of ceramic material, a movable switch element supported at the top 125 of the column and means extending axially through the column for operating the switch element.

2. High tension switch mechanism including a hollow column of ceramic material, 130

a movable switch element supported at the top of the column and means including a column of ceramic material extending axially through the said column for operating the switch element.

3. High tension switch mechanism including a hollow column composed of a plurality of hollow tile sections in superposition, a

switch element supported at the top of the column and means for operating the switch element including a column composed of hollow tile sections and extending axially through the said column.

In testimony whereof, I affix my signature.

CARL G. KOPPITZ.
